DESIGN FOR A REVOLVING FILE

Otto Decker, New York, N. Y.

Application November 27, 1946, Serial No. 135,129

Term of patent 3½ years

(Cl. D33—19)

To all whom it may concern:

Be it known that I, Otto Decker, a citizen of the United States of America and a resident of the city of New York, in the county of Queens and State of New York, have invented a new, original, and ornamental Design for a Revolving File, of which the following is a specification, reference being had to the accompanying drawing, forming a part thereof.

Fig. 2 is a front view thereof, and

Fig. 3 is a top view thereof.

I claim:

The ornamental design for a revolving file, substantially as shown.

OTTO DECKER.
